CONVEYER FOR BOMBS OR THE LIKE

Thomas P. Duncan, Jr., Newport News, Va.

Application February 21, 1942, Serial No. 431,871

2 Claims. (Cl. 102—2)

This invention relates to a conveyer for bombs or the like and it is primarily an object of the invention to provide a device of this kind adapted to be conveyed by the wind at a predetermined altitude, together with means for automatically allowing dropping of a bomb at an approximate predetermined period of time after the device has been freed for transit.

The invention also has for an object to provide a device of this kind wherein the carrier comprises a balloon or the like and wherein is employed a connector for coupling a bomb to the carrier, said connector constituting a timing element for automatically dropping the bomb at an approximately predetermined period of time after the device has been freed for transit.

A still further object of the invention is to provide a device of this kind which is conveyed toward its objective by the prevailing winds and in a manner whereby an attack can be made free of sound or warning of any kind.

An additional object of the invention is to provide a timing element which also constitutes a connector for initially coupling a bomb to be dropped to a balloon or the like, said timing element having a portion of a highly combustible material, together with means comprised in the timing element to create a heat sufficient to ignite said portion of the element to effect release of the bomb.

Another object of the invention is to provide a device of this kind comprising a balloon inflated with a combustible gas, and wherein is provided a connector for coupling the bottom to the balloon, said connector being inflammable, together with means carried by the connector for igniting the same and/or igniting the gas released from within the balloon.

The invention consists in the details of construction and in the combination and arrangement of the several parts of my improved conveyer for bombs or the like whereby certain important advantages are attained, as will be hereinafter more fully set forth.

In order that my invention may be better understood, I will now proceed to describe the same with reference to the accompanying drawing, wherein:

Figure 1 is an elevational view of a conveyer for an aerial bomb constructed in accordance with an embodiment of my invention.

Figure 2 is an enlarged sectional view taken substantially on the line 2—2 of Figure 1, with certain of the parts in elevation.

Figure 3 is a fragmentary sectional view illus-

trating a further embodiment of the invention.

As disclosed in the accompanying drawing, B denotes a balloon, preferably inflated by hydrogen or other suitable gas. The balloon B is provided with a depending neck 1 which after the desired inflation of the balloon, will be slipped over an end portion of a conductor or coupling element E and securely held thereto by a surrounding band 2, preferably of an adhesive type. I do not, however, wish to limit myself as to any particular manner of securement. The applied element E serves as a plug for sealing the neck 1. The balloon B is preferably inflated with hydrogen or other combustible gas.

The element E, as herein disclosed, constitutes a capsule comprising a body member M, a tip member T and a cap member C. In the present embodiment of my invention each of these members M, T and C is made of a highly combustible material, such as cellulose acetate. The body member M is tubular and open at its upper end and closed at its lower end and slipping upon the closed end portion is the tubular extremity 3 of the tip member T.

The outer end portion 4 of the tip member T is conoidal, with its apex portion solid, such solid portion having an inner concave face 5 provided at its axial center with a socket 6. Within the socket 6 is inserted an igniter 7, preferably in the form of a pellet, and this igniter is of a material to become effective under the action of a suitable acid solution, such as a solution of acetic acid or sulphuric acid, although acetic acid is preferred.

Inserted through the closed end of the body member M at its axial center is a plug 8 of a metal easily eaten by an acid solution, such as a magnesium alloy or the well known Dow metal which is a metallurgical standard metal. This plug 8 is provided at its lower or outwardly facing end with a countersink 9 of a depth to provide the central portion 10 at the upper or inner end of the plug 8 to be of desired thickness.

After the igniter or pellet 7 has been placed within the socket 6, the tip member 8 is placed upon the closed end portion of the body member M. The opposite end portion of the body member M is closed by the applied cap member C, herein disclosed as of a slip type, and said members T, M and C may be effectively held in desired assembly by application of collodion, by subjecting said parts to requisite heat or in any other manner which may be preferred.

The cap member C at its axial center is provided therethrough with an opening 11 to al-

low the desired supply of acid solution to be poured into the body member M. The completed connector or capsule is then applied to the inflated balloon B, as hereinbefore stated. It has been found in actual tests that by the use of the band 2 there is a loss of only 10% of the balloon lift over a period of eleven and one-half days.

The conoidal portion 4 of the tip member T at the apex thereof is provided with an outstanding shank 11 of desired length and terminating in an eye member 14 and which eye member provides means for connection with the tail end of an incendiary bomb I or the like. The apex of the conoidal portion 4 in the present embodiment of the invention is enlarged to provide a substantially spherical head 13 which can be readily inserted within a grommet carried by the tail end of the bomb I should such a coupling be desired. It is to be stated, however, that I do not wish to limit myself to any particular means whereby the connector E is secured to the bomb. It is to be pointed out that the connector E is small in size and the completed and charged connector does not exceed a total weight of more than one ounce and the complete assembly including the standard incendiary bomb does not exceed a weight of more than two pounds. Of course, such weight can be decreased or increased as may be preferred but it has been found in practice that the weight just given assures a high degree of effectiveness.

The igniter or pellet 7, as hereinbefore stated, can be made of any preferred material but it has been found in practice that phosphorus or hexachlorethane can be employed to advantage.

In practice, with the acid solution in the body member M of required variance precalculated by nephoscope readings on a trial balloon in ratio to desired time interval relative to objective distance, the balloon B is inflated so that it will rise to a definite altitude with a given load so that the same will have a zero lift at the desired height as established from the theodolite computation on a trial balloon or from minute observations on a trial balloon with 40 gram lift. After the balloon has been inflated to this computed diameter, its neck or stem 1 is rolled over the body member M of the element E and secured thereto. With the element E in proper connection with the bomb I, the complete assembly is turned loose and will rise to its slip stream altitude and will be carried by said slip stream until the acid eats through the central portion 10 of the plug 8, releasing the gas in the balloon over its computed objective. The acid released from the body portion M will drop into the tip member T and ignite the igniter or pellet 7, resulting in the burning of the tip member T and which burning is further facilitated by ignition of the escaping gas. This burning of the tip member T results in the release of the bomb I to allow the same to drop on its objective area which it has approached without sound or warning.

If the acid should fail to ignite the igniter or pellet 7, the escaping gas will pass or escape out through the openings 16 provided in the wall

of the tip member closely adjacent to the inner face 5 thereof, so that dropping of the bomb is assured. These openings 16 will also allow the discharge therethrough of the released acid solution to assure the desired escape of the gas.

As illustrated in Figure 3 of the drawing, after the desired charge of acid solution has been placed within the body member M, the opening 11 of the cap member C may be suitably sealed or closed, as indicated at 17, whereby escape of gas from the balloon is prevented. When this opening 11 is closed there is added to the gas within the balloon a small amount of chlorine gas, about 3%, so that after the bomb has been dropped, the balloon will continue to travel with the slip stream and later on said balloon B will be caused to burst as a result of the expansion of the gas therein effected or ignited by the sun rays activating the chlorine hydrogen mixture.

It has been found in practice that with the use of a 7% solution of acetic acid and with the central portion 10 of the plug 8 of $\frac{1}{16}$ " thick, approximately three hours' time will elapse after the release of the assembly before the acid will eat through the portion 10 of the plug 8. It will, therefore, be obvious that by varying the strength of the acid solution and/or by varying the thickness of the portion 10, or both, this time may be regulated within certain limits.

From the foregoing description it is thought to be obvious that a conveyer for bombs or the like constructed in accordance with my invention is particularly well adapted for use by reason of the convenience and facility with which it may be assembled and operated.

I claim:

1. A conveyer for an aerial bomb comprising a balloon, a connector carried thereby for coupling a bomb to the balloon, said connector being hollow with its outer end closed and its opposite end in communication with the interior of the balloon, the side wall of the connector having one or more openings therethrough, means for closing the flow of gas within the balloon out through the opening, and means carried by the connector and operating while the conveyer is in flight for opening the flow of the gas through the connector and out through the opening, said connector being combustible, and an igniter carried by the connector.
2. A conveyer for an aerial bomb comprising a balloon and a connector carried by the balloon, said connector comprising a hollow body, means carried by the body for coupling the same to a bomb, a wall dividing the hollow body into two chambers, said wall having an opening affording communication between the two chambers, a member closing said opening, an acid within one of the chambers for disintegrating said closure member to allow the acid to flow from one chamber to the other, and an igniter within the second chamber made effective under the action of the acid delivered within the second chamber, the portion of the body member adjacent said second chamber being combustible, the burning of said portion freeing the bomb.

THOMAS P. DUNCAN, JR.
